UNITED STATES PATENT OFFICE.

HAROLD L. HAYNES, OF LAKEWOOD, OHIO, ASSIGNOR TO LARIMER COMPANY, OF AURORA, ILLINOIS, A CORPORATION OF ILLINOIS.

PERIODIC ROTARY AND CAM SWITCH.

Application filed April 27, 1925. Serial No. 26,179.

To all whom it may concern:

Be it known that I, HAROLD L. HAYNES, a citizen of the United States, residing at Lakewood, in the county of Cuyahoga and State of Ohio, have invented new and useful Improvements in Periodic Rotary and Cam Switches, of which the following is a full, clear, concise, and exact description, reference being had to the accompanying drawing, forming a part of this specification.

My invention relates to circuit controlling devices.

One of the objects of my invention is to provide a circuit controlling device for controlling the circuit to intermittently illuminated electric signs which will cause contact to be successively made with different portions of a rotatable member to insure even wear and good contact.

Further objects will appear from the description and claims.

In the drawings, in which an embodiment of my invention is shown,

Figure 1 is a plan view of a circuit controlling device;

Fig. 2 is a side elevation with the cover shown in section;

Fig. 3 is a horizontal section substantially on the line 3—3 of Fig. 2;

Fig. 4 is a section substantially on the line 4—4 of Fig. 3;

Fig. 5 is a detail of the contact shoes; and

Fig. 6 is a diagrammatic view showing the wiring connection.

Referring to the drawings in detail, the construction shown comprises a rotatable drum 1 of conducting material, a pair of pivotally mounted contact shoes 2 of conducting material, insulated from each other and oscillatable into and out of engagement with respect to the inner surface of said drum, a rotatable cam 3 coaxial with said drum for controlling the oscillation of said shoes, and means for driving said drum and cam at different speeds relative to each other, whereby the contact shoes will successively engage different portions of the inner surface of the drum.

A pair of magnetic blow-out devices 4 are provided adjacent the point of contact between the oscillatable shoes and the rotatable drum for lessening the arc when the contact is broken.

The means for driving the shoe controlling cam 3 and rotatable drum 1 at different speeds comprise the bevel gear 5 driven from the motor 6 through suitable transmission described hereinafter, a shaft 7 on which the bevel gear 5 is mounted, and on which the shoe controlling cam 3 also is mounted, a spur gear 8 secured to rotate with the shaft 7, a double faced spur gear having one face 9 meshing with the spur gear 8, another spur gear 10 slightly larger in diameter than the spur gear 8 and meshing with the other face 11 of the double faced spur gear, and a sleeve 12 rotatable with the spur gear 10, on which sleeve the rotatable drum 1 is mounted to rotate therewith. Because of the difference in diameter of the spur gears 8 and 10, the contact drum 1 will rotate at a slightly slower speed than the cam 3 which controls the oscillation of the contact shoes 2, so that each time the cam revolves, it will bring the contact shoes into engagement with a different spot on the inside of the contact drum.

The contact shoes are oscillatably mounted at 13 and 14 on the vertical extending bracket 15, which also serves as a cap for the bearing in which the end of the shaft 7 is mounted. The shoes are insulated from each other and from the other parts of the apparatus by means of insulation pieces 16 secured to the pivoted arms 21, the contact shoes being mounted on these pieces 16. Each contact shoe is provided with a binding screw 17, from which a flexible connection 18 leads to the binding post 19 for the respective magnet coil 20 forming part of the magnetic blow-out construction (see Figs. 3 and 6).

In order that the contact shoes may be yieldingly pressed into engagement with the inner face of the contact drum, a yielding lost motion transmission is provided between the cam 3 and each of the pivoted shoe-carrying arms 21, this yielding transmission comprising an arm 22 pivotally mounted on the pivoted arm 21 and having a roller follower 23 engaging the cam 3, and a leaf spring 24 secured to the pivoted arm 21 and engaging the follower arm 22. A pin and slot connection is provided at 25 between the two pivoted arms 21 and 22 which permits the necessary lost motion between the two. In order to move the contact shoes away from the contact drum when released by the

- rotation of the cam, a coil torsion spring 26 is provided, one end of which is secured to the supporting bracket 15, and the other of which is secured to the pivoted arm 21.
- 5 Each of the magnet coils 20 for the magnetic blow-outs is provided with another binding post 27, from which connections lead to the binding screws 28 (Fig. 6) to which the controlled circuit 29 is connected.
- 10 The armatures 20 for the magnets of the magnetic blow-out devices straddle the periphery of the rotatable drum 1 at points adjacent the contact shoes 2, so that when the circuit is broken by the disengagement 15 of the shoes with respect to the drum, the collapse of the magnetic field will lessen the arc in a well understood manner.

The magnetic blow-outs are mounted on a horizontally extending arm 31 secured to 20 an L-shaped bracket 32 (Fig. 3) which in turn is secured to the supporting bracket 33 on which the transmission for the drum and cam are mounted. The binding screws 27 and 28 are mounted on an insulating piece 25 34 secured at the top of the supporting brackets 33 and 35. A suitable housing 36 may be provided for enclosing the entire mechanism. A tubular nipple 37 is provided for the wires leading to and from the 30 apparatus.

The transmission from the motor 6 to the bevel gear 5 previously referred to comprises a crank disc 38 rotatable with the motor shaft and provided with a crank pin 39, a crank disc 40 having a notch 41 to receive the crank pin 39, so that the crank disc rotates with the crank pin, suitable worm gear transmission 42 driven from the crank disc 40, a bevel gear 43 driven from this 40 worm transmission 42, a bevel gear 44 meshing with the bevel gear 43, a shaft 45 on which the bevel gear 44 is mounted, and a bevel pinion 46 mounted on the shaft 45 and meshing with the bevel gear 5 previously 45 referred to.

Suitable electrical connections lead from the motor 6 to the two binding screws to which the power lines for the motor are connected. As shown in Fig. 6, the circuit 50 is from the line 49 through the conductor 50 to the binding screw 28, through the conductor 51 to the binding screw 27, through the magnet coil 20 to the binding screw 19, through the flexible conductor 18 to the binding screw 17 on the contact shoe 2, through the rotatable drum 1 to the other contact shoe 2, from the binding screw 17 on this contact shoe through the flexible conductor 18 to the binding screw 19 of the 55 other magnet coil 20, through the magnet coil to the other binding screw 27, from this binding screw 27 through the conductor 52 to the binding screw 28 and thence through the conductor 29 controlled devices to the 60 other side of the line 49.

In operation, the rotatable drum and contact controlling cam are driven at slightly different speeds, so that each time one of the shoes is pressed outwardly into engagement with the rotatable drum, it engages the 70 drum in a different place, to insure even wear on the drum and good contact between the parts. When the contact is broken the magnetic blow-out acts in a well known manner to lessen the arc. The yielding lost 75 motion transmission from the cam to the contact shoe insures a firm, but yielding engagement between the contact shoe and drum.

In order to permit an extremely quick 80 break between the contact shoes 2 and the contact drum 1, a lost motion is provided between the drive shaft 7 and cam 3. This lost motion connection comprises a pin 53 extending diametrically through the shaft 85 7 and having its ends engaging the slots 54 in the hub of the cam 3. This lost motion connection permits the cam to snap forward quickly the instant the rollers 23 slip off from the abrupt shoulders 55. This snapping forward of the cam 3 lets the arms 21 move inwardly rapidly to effect a quick break between the shoes 2 and the drum 1. During the next half-revolution of the cam 3 the drag of the rollers 23 on the cam 3 95 retards the cam until the pin 53 catches up with the cam and drives it positively.

I claim:

1. A circuit controlling device comprising a rotatable drum of conducting material, a pair of pivotally mounted contact shoes of conducting material insulated from each other and oscillatable into and out of engagement with respect to the inner surface of said drum, a rotatable cam coaxial 100 with said drum for controlling the oscillation of said shoes, and means for driving said drum at a speed different from the speed of said cam whereby the contact shoes will successively engage different portions 105 of the inner surface of the drum.

2. A circuit controlling device comprising a rotatable member having a circular contact surface, a pair of contact pieces insulated from each other, and movable into 115 and out of engagement with respect to said circular contact surface, said contact surface being a conductor and electrically connecting said contact pieces when in engagement therewith, means for rotating said rotatable member, and means for intermittently bringing both of said contact pieces into and out of engagement successively with respect to different portions of said contact surface.

3. A circuit controlling device comprising a rotatable member having a circular contact surface, a contact piece movable into and out of engagement with respect to said circular contact surface, means for rotating 125

said rotatable member, and rotatable means coaxial with said rotatable member for intermittently bringing said contact piece into and out of engagement successively with respect to different portions of said circular contact surface.

4. A circuit controlling device comprising a rotatable member having a circular contact surface, a contact piece movable into and out of engagement with respect to said circular contact surface, means for rotating said rotatable member, and means for intermittently bringing said contact piece into and out of engagement successively with respect to different portions of said circular contact surface, comprising a rotatable cam co-axial with said rotatable member and means for rotating said cam at a different speed from that of the rotatable member.

5. A circuit controlling device comprising a rotatable drum of conducting material, a pair of pivotally mounted contact shoes of conducting material insulated from each other and oscillatable into and out of engagement with respect to the inner surface

of said drum, a rotatable member coaxial with said drum for controlling the oscillation of said shoes, and means for driving said drum at a speed different from the speed of said member whereby the contact shoes will successively engage different portions of the inner surface of the drum.

6. A circuit controlling device comprising a rotatable member having a circular contact surface, a contact piece movable into and out of engagement with respect to said circular contact surface, means for rotating said rotatable member, and means for intermittently bringing said contact piece into and out of engagement successively with respect to different portions of said circular contact surface, comprising a second rotatable member coaxial with said first rotatable member, and means for rotating said second member at a different speed from that of the first rotatable member.

In witness whereof, I have hereunto subscribed my name.

HAROLD L. HAYNES.
